EXPANSION VALVE

Edward R. De Luiz, Highland Park, Mich.

Application June 22, 1933, Serial No. 677,013

5 Claims.

(CL. 50—26)

This invention relates to valves and particularly to a type adaptable for use in connection with refrigerating mechanism, the principal objects being the provision of a device of this type 5 that is simple in construction, efficient in operation, economical to produce and of relatively smaller size than valves of the same capacity heretofore proposed.

Other objects include the provision of a valve 10 of the type described that includes a minimum number of operating parts of simple design capable of being easily assembled in accurate relation to each other; to provide a valve which permits accurate and positive seating of the valve 15 element; to provide an expansion valve embodying but a single spring; to provide a valve structure having a floating valve or novel construction; to provide a valve structure having a full floating valve positively operated in both directions of movement; to provide an expansion valve 20 in which a full floating valve is connected to the pressure operated member thereof for positive inter-related movement; to provide a valve of the type described having a full floating valve 25 element positively movable vertically in opposite directions; and to provide an expansion valve having novel means for positively placing it in open position.

Other objects include the provision of a novel 30 form of needle valve and connection with its operating member, insuring perfect sealing of the valve at all times.

Further objects include the provision of a novel 35 means for operating an expansion valve; the provision of a novel thermostatically controlled expansion valve; the provision of a novel connection between a thermostatically operated element and an expansion valve whereby the absorption 40 of heat in the expansion valve will not affect the operation of the thermostatic device; and the provision of a thermostatically operated expansion valve having a novel form of connection between the thermostatic element and the valve proper permitting ease and accuracy of adjustment 45 thereof.

The above being among the objects of the present invention, the same consists in certain novel features of construction and combination of parts to be hereinafter described with reference to the 50 accompanying drawing, and then claimed, having the above and other objects in view.

In the accompanying drawing which illustrates suitable embodiments of the present invention and in which like numerals refer to like parts throughout the several different views,

Fig. 1 is a vertical sectional view taken centrally through an expansion valve.

Fig. 2 is a vertical sectional view taken on the line 2—2 of Fig. 1.

Fig. 3 is a fragmentary horizontal sectional view taken on the line 3—3 of Fig. 1.

Fig. 4 is a horizontal sectional view taken on the line 4—4 of Fig. 1.

Fig. 5 is a fragmentary, partially sectioned, partially broken, enlarged view showing with greater clearness the construction of the connection between the valve proper and the member to which it is directly connected in the expansion valve shown in the previous figures.

Fig. 6 is a view similar to Fig. 1 but showing the construction therein modified for operation by a thermostatic element.

As is well understood in the art, expansion valves are used in connection with refrigerating apparatus for controlling the flow of liquid refrigerant from the high pressure side of the system to the low pressure side of the system. Such valves are controlled in a variety of different ways such, for instance, as by the pressure in the low side of the system, the temperature of the evaporator or the space which the evaporator cools, and in many cases by a float. One of the principal features of the present invention is in the construction of a valve itself which is applicable for use in connection with any of the above types 30 of expansion valves or apparatus but, for the purpose of illustration only, the invention is herein illustrated in connection with an expansion valve of the pressure operated type and one of the thermostatically operated type, the application of 35 the valve itself to these structures involving further novel features constituting additional features of the present invention.

It is also well understood in the art that in connection with such valves, except for the float 40 control type, it is necessary to have a movable wall of some suitable type to serve either as a pressure responsive element, or as a seal, or both, and while in the broader aspects of the present invention such movable wall may take the form 45 of a bellows, a diaphragm or a piston, the former is shown as being preferred by way of illustration, although in some of the narrower phases of the present invention as will hereinafter be specifically pointed out and claimed, the bellows 50 forms a part of a new and novel combination.

Referring now to the drawing and particularly to Figs. 1 to 5 inclusive, an expansion valve is shown as including a casing 10 through which refrigerant is adapted to flow as controlled by the 55

mechanism enclosed therein. The liquid refrigerant is adapted to be introduced into the casing, as best illustrated in Fig. 4, through a connection member 12 threaded into a passage 14 formed in the casing 10, a screen 16 of cylindrical formation and having a closed end (not shown) being suitably associated with the connection member 12 and projecting within the passage 14 in spaced relation to the walls thereof so as to filter the refrigerant flowing to the valve and remove foreign material therefrom. The passage 14 is connected by a cross passage 18 with the lower end of a vertically extending passage 20 opening upwardly into the interior of the casing 10 adjacent the bottom thereof, the upper end of the passage 20 having plug 22 centrally apertured as at 23 threaded thereinto and which serves to provide a seat for a needle type of valve. The outlet passage 24 is shown as extending vertically downwardly through the lower end of the casing, although it may be positioned otherwise if desired, and is suitably threaded for reception of a suitable pipe or tube coupling (not shown).

25 The upper wall of the casing 10 in vertical alignment with the passage 20 is provided with a threaded opening 26 normally closed by the plug 28 and through which opening the plug 22 and other parts of the valve structure may be 30 inserted or removed. The plug 28 is provided with a recess 30 centrally disposed in its lower face, the purpose of which will be later disclosed.

The right hand end of the casing 10 is originally formed fully open and this open end is closed 35 by a bellows 32 having a head 34, and an open end which is sealed to a ring 36, the periphery of the ring being received against a shoulder 38 formed at the open end of the casing 10 and to which the ring 36 is suitably sealed as by solder. A cap 40 is screwed onto the open end of the casing 10 over the open end of the bellows 32 and is provided with a central boss 42 axially aligned with the bellows 32. This boss is provided with a central axial opening in which is threadably received a headed bolt 44, the head of which projects into the bellows 32 and into relatively close but normally spaced relation with respect to the head 34 thereof. A cup member 46 is positioned within the bellows 32 and its bottom is soldered or otherwise fixed to the head 34. The open end of the cup 46 which extends to a point adjacent the open end of the bellows 32 is inwardly turned at its open end to form an annular flange 48 within which is removably received 50 a split ring or washer 50 which serves as a seat for a conical coil spring 52 constantly maintained under compression between the ring 50 and the head of the bolt 44. By threading the screw inwardly or outwardly in the boss 42 it will be 55 apparent that the tension of the spring 52 acting to collapse the bellows 32 may be varied, and consequently the amount of suction within the casing 10 necessary to expand the bellows 32 a given amount may be correspondingly varied. Preferably the exterior surface of the boss 42 is threaded and receives thereon a smaller cap member 54 which may be sealed to the cap 40 through the employment of a suitable gasket such as 56.

Pivots mounted within the casing between 70 two cone pointed pins 58 threaded through opposite walls of the casing 10 is a bell crank 60 one arm 62 of which extends to the left as viewed in the drawing in a generally horizontal direction and the other arm 64 of which extends in 75 a generally downwardly direction and is provided

with a partially cylindrically formed end 66. The lengths of the arms 62 and 64 may, of course, be varied in their respective lengths as necessity or desires dictate. The end 66 is relatively closely received in a vertically extending rectangular opening 68 provided in a bracket 70 which is soldered or otherwise suitably secured to the outer surface of the head 34 of the bellows 32, this connection being such as to permit rectilinear movement of the end of the bellows 32 and the bracket 70 while causing corresponding positive pivotal movement of the bell crank 60 in either direction.

The free end of the arm 62 of the bell crank 60 is provided with a relatively large vertically disposed opening 72 in axial alignment with the aperture in the plug 22 when the arm 62 is in horizontal position and threadably received in the opening 72 is a collar or ring member 74. Now referring to Fig. 5 in which this portion of the apparatus is shown in greater detail, it will be noted that the collar 74 is provided with a bore 76 which is of smallest diameter at a point approximately midway its length and flares outwardly in both directions therefrom. The collar 74 is also provided with a transverse opening 78 at its point of minimum internal diameter in which is received a pin 80. A valve or valve element 82 of the needle type is relatively closely received in the bore 76 at its point of minimum diameter and depends vertically therefrom, its pointed end 84 being received within the aperture 23 of the plug 22 and cooperating therewith to control the flow of fluid through the plug 22 into the casing 10. At the point where the valve element 82 projects through the collar 74 it is provided with a transverse opening 86 in which the pin 80 is relatively closely received. The opening 86, in a manner similar to the bore 76, is of minimum diameter adjacent the midpoint 40 of its length and flares outwardly in either direction therefrom, the walls of the opening 86 at the point of minimum diameter thereof relatively closely receiving the pin 80. As will be apparent, with this construction the valve element 82 is 45 so supported relative to the arm 62 of the bell crank 60 that the point 84 of the valve element is allowed a limited amount of free floating movement in all directions except axially and consequently the point 84 is always capable of freely 50 moving so as to properly accommodate itself to its seat in the plug 22.

As will be noted, the upper end of the valve element 82 projects upwardly beyond the upper end of the collar 74 and is provided ample clearance for its movement in the opening 30 in the plug 28. The upper face of the collar 74, which is of greater diameter than the opening 30, is positioned in normally adjacent but spaced relation with respect to the lower face of the plug 28, and the spacing between these parts is such as to permit contact of the collar 74 with the cap 28 for the purpose of limiting excessive expansive movement of the bellows 32 should the occasion arise, and thus prevent possible rupture of the bellows from such cause. Likewise, engagement of the valve element 82 with the plug 22 limits movement of the bellows in the opposite direction.

The construction of the valve element 82 and its supporting mechanism is of particular importance for the reason that when properly constructed and assembled it provides a positively operated valve that is always positive in its seating and free of any sticking tendency. This is of utmost importance in connection with refrigerat-

ing mechanism as the lack of a proper seat for the valve element in expansion valves is one of the chief causes of trouble in refrigerating apparatus at the present time. In order to illustrate how accurately the valve element 82 may be located and its seat in the plug 22 formed with the present apparatus, it may be mentioned that the passage 20 and the opening for the pin 58 may be formed in the casing 10 through the use of a single suitable jig, as will be apparent to those skilled in the art which will thereby accurately locate these openings relative to each other. This passage and these openings may then be tapped, the plug 22 inserted in place, and then the bell crank 60 may be introduced through the opening 26 and the pins 58 threaded through the casing and into a position to engage the bell crank 60. A suitable locating tool (not shown) may now be threaded through the opening 12 in the arm 62 of the bell crank 60 and located in the aperture 23 of the plug 22. The pins 58 may then be threaded either in and out until it is apparent that the locating tool is properly located in the aperture 23 and the pins 58 exert the proper pressure in their bearings in the bell crank 60 without interfering with the proper free pivotal movement thereof. Solder, such as 88, may then be applied to the casing 10 over the ends of the pins 58 to seal the casing from possible leakage at this point and to lock the pins in adjusted position. At this point the screw 44 may be threaded inwardly until its head contacts the head 34 of the bellows 32 thus positioning the bell crank 60 in a definite location. The locating tool 35 may now be removed from the opening 12 and a suitable bushing may now be inserted in the opening 12 and employed for guiding a suitable tool for forming a shallow seat for the valve element 82 at the upper margin of the aperture 23 in the plug 22, and after such tool and bushing is removed the collar 14 may be slipped over the valve element 82, the pin 80 inserted in place and this assemblage threaded into the opening 12 in the arm 62 to its final position.

45 After this mechanism has been located in the manner described and the screw 44 backed off, it will be apparent that, because of the freedom of the universal movement of the valve element 82 in the arm 62 of the bell crank, and particularly in view of the fact that the valve element is pendant, or positioned with its axis vertically and hanging from the pin 80, the coned end 84 of the valve element 82 will always find its proper seat upon closing movement of the valve. This is particularly true in view of the fact that the bell crank 60 will always be in the same position when the valve is moved to closed position and further due to the fact that the valve element 82 will seldom be lifted from its seat a distance greater than .010 of an inch during operation of the valve.

60 The operation of the above described valve will of course be apparent to those skilled in the art and briefly may be stated as follows: When the pressure on the low side of the system drops below a predetermined point, which may be variably controlled by manipulation of the screw 44 as previously described, the length of the bellows 32 will be increased, the head 34 of the bellows moving to the left as viewed in the drawing. Movement of the head 34 will cause an equal and positive movement of the bracket 70 which in turn will cause an equal and positive movement of the end 66 of the bell crank 60, causing the bell crank to pivot about its pivotal axis in a clockwise direction as viewed in the figures. This movement of

the bell crank will positively cause the free end of the arm 62 thereof to move upwardly and in moving upwardly will positively lift the valve element 82 and retract the end 84 thereof partially from the aperture 23 in the plug 22 and will thus permit liquid refrigerant to flow into the casing through the aperture 23 and out of the casing through the passage 24 into the low pressure side of the system. As soon as the pressure in the low pressure side of the system increases sufficiently to permit the spring 52 to contract the bellows 32 to such an extent as to move the valve element 82 again to closed position, the flow of liquid refrigerant into and out of the casing 10 will be discontinued. Furthermore, rise in pressure on the low side of the system including the interior of the casing 10, will act on the bellows 32 to additionally force the valve point 84 against its seat. It is to be noted that during opening movement of the valve, the valve element 82 is positively moved toward opened position and, likewise, during closing movement of the valve the valve element 82 is positively moved toward closed position and the end 84 of the valve element is always capable of floating so as to insure its finding is correct and perfect seat in the plug 22. In this respect it will also be understood that because of the positive support for the bell crank 60 which insures the end 62 following the same path of movement at all times, the pressure of the spring 52 can have no effect whatsoever on tending to divert the end 84 of the valve away from proper seating position. It is also noted that the structure involves a minimum number of operating parts which may be assembled into a relatively small structure which makes for ease and economy in production. Also, that because of the construction and arrangement of the parts, any particles of grit or other foreign matter that may find its way into the casing will not affect the proper movement of the parts or interfere with the proper working of the mechanism. It may also be noted that should it be desired for any reason or other to positively hold the valve in open position the cap 54 may be removed and the screw 44 threaded inwardly until its head contacts with the bottom of the cup 46 and moves the valve to open position. This feature not only serves as an aid in the proper assembly of the device, but also provides means whereby positive opening movement of the valve may be accomplished should the occasion arise. By threading the screw 44 in the opposite direction to increase the compression of the spring 52, it enables the usual cooling unit or evaporator of a refrigerating system to be removed without danger of loss of refrigerant through the expansion valve.

65 In Fig. 6 is illustrated the application of substantially the same mechanism illustrated in the previous figures to an expansion valve of the thermostatically operated type. As will be noted in this figure, the parts at the left hand end thereof are identical to the parts previously described except that a cap 90 of different design is substituted for the cap 40 shown in Fig. 1, the metal cup 46a within the bellows 32 has been modified to provide an inwardly facing cone-like projection 92 centrally of its bottom and the spring 52 has been replaced by a spring 94 of slightly different shape and size. The cap 90 in this case threads onto the casing 10 in substantially the same manner as that previously described but is provided with a threaded portion 96 on which is threadably received what may be known as an insulating spacing casing 98, preferably formed from 70

suitable non-metallic heat insulating material as, for instance, rubber or some phenolic condensation product such as that marketed under the name of Bakelite.

5 The casing 98 is provided with a head 100 having a central axially projecting boss 102 in which is closely but slidably received the right hand end of a tube 104. The tube 104 is preferably formed of the same material as the casing 98. The cap 90 is provided with a centrally apertured boss 106 which is internally threaded for cooperative engagement with the corresponding threaded portion of the tube 104 which projects therethrough. The right hand end of the boss 106 as viewed in the figure may be inwardly tapered on its end face and the exterior of the boss threaded and provided with a nut 108 which may cooperate therewith to compress packing such as 110 about the tube 104 so as to effect a gland therefor. The 10 left hand end of the tube 104 projects into the cup 46a in the bellows 32 and at its extremity is provided with a peripheral flange 112 between which and the ring 50 the coil spring 94 is maintained under compression.

15 25 Midway of its length the casing 98 is preferably provided with an aperture such as 114 and the tube 104 in approximate alignment transversely with the opening 114 is preferably provided with an hexagonal surface 116 enabling a wrench to be inserted into the casing 98 through the aperture 114 and into engagement with the tube 104 to permit rotation thereof and thus vary the stress of the spring 94 for the purpose of modifying the pressure required to actuate the 30 bellows 32 and consequently the valve element 82.

35 Threaded onto the right hand end of the casing 98 is another casing 120 having an end wall 122. Within the casing 120 is a bellows 124, the head of which is fixed against movement to the end wall 40 122. The left hand end of the bellows 124 is provided with a head member 126 the central portion of which is depressed inwardly relative to the bellows to form a cup 128 and the bottom of the cup is formed to provide an inwardly extending cone-like projection 130 similar and opposed to the projection 92 previously described. Freely 45 slidably received within the tube 104 and extending between the projections 92 and 130 is a rod 132 which is preferably formed of the same material as the casing 98 and tube 104. The interior of the bellows 124 communicates through a tube 134, which is usually of the capillary type, with the usual control bulb or feeler leg 136, it being understood that the bulb 136, tube 134 and bellows 50 55 124 is filled, partially or otherwise, with a suitable refrigerant adapted to vaporize at a desired given temperature, and that the bulb 136 is positioned in, against or in proximity to the object or chamber, the temperature of which it is desired to control. Obviously, when the temperature of such chamber increases sufficiently to cause a portion of the refrigerant in the bulb 136 to vaporize, the increased pressure in the bulb 136 caused by such vaporization is transmitted through the tube 134 60 65 to the bellows 124 and tends to expand the bellows 124. Upon expansion of the bellows 124 the rod 132 will be moved to the left, as viewed in the figure, and cause a like movement of the head of the bellows 32 which, as previously described, 70 will cause the valve element 82 to be lifted from its seat and permit liquid refrigerant to flow into the casing 10 and into the low pressure side of the refrigerating system causes a predetermined drop in the temperature of the part con-

trolled by the bulb 136, the refrigerant in the bulb 136 will be condensed, causing a drop in pressure in the tube 134 and bellows 124 which will permit the spring 94 to contract the bellows 32 and move the valve element 82 to closed position.

5 It is to be particularly noted that in connection with thermostatically operated expansion valves of the general type indicated, considerable difficulty has been experienced in previously suggested 10 constructions due to the fact that the connection provided between the member moved directly by the tube 136, the bellows 124 in the present case, has had some form of metallic connection with the casing of the expansion valve proper and, due 15 to the fact that the liquid refrigerant flowing through the expansion valve reduces the temperature thereof to a material degree, heat is absorbed from the wall moved by the tube 136 and causes the gasified refrigerant therein to be liquefied, thus either destroying or at least rendering 20 inaccurate or unsatisfactory the accurate results for which the device is intended. With the present construction by the employment of the heat insulating casing 98, tube 104 and rod 132 the 25 possibility of heat absorption from the bellows 124 and liquid contained therein by the expansion valve proper is entirely eliminated so that any influence of the expansion valve through heat absorption upon the proper controlling movement 30 of the tube 136 is entirely eliminated. Obviously 35 the same advantages occur in connection with this form of construction as occur in the construction described in the previous figures, in addition to those above enumerated.

40 It will be obvious to those skilled in the art that the mechanism herein shown and described is capable of many other applications and is also capable of various modifications and changes without materially affecting the invention involved and, accordingly, it will be apparent that formal changes may be made in the specific embodiment of the invention described without departing from the spirit or substance of the broad invention, the scope of which is commensurate 45 with the appended claims.

I claim:

1. In a valve structure, in combination, a casing having a valve seat, a member in said casing movable along a fixed path and having an opening 50 therein, said opening having a wall portion of restricted dimensions and the walls thereof flaring outwardly from said portion, a needle valve passing through said opening and relatively closely received by said restricted wall portion, said needle valve having a transverse opening therethrough, a central portion of the last mentioned opening being of restricted diameter, and a pin 55 extending through said opening in said pin and fixed against movement relative to said member at the point of wall restriction of said opening therein, the point of said valve lying in cooperative relation with respect to said seat.

2. In a valve structure, in combination, a casing having a valve seat provided therein, a bell 65 crank pivotally supported in said casing, an arm of said bell crank having a threaded opening therein, an apertured plug threadably received in said opening, the aperture in said plug being of restricted diameter between its ends and flaring outwardly therefrom, a needle valve projecting through said aperture with its point in cooperative relation with respect to said seat, said needle valve having a transverse opening therethrough at the point of restriction of said aper-

ture in said plug, said transverse opening being of restricted diameter between its ends and flaring outwardly therefrom, said plug also having a transverse opening therethrough at the point of restriction of the aperture therein, and a pin extending through said transverse apertures.

5. In a valve structure, in combination, a casing having a valve seat therein and an opening therein, a bellows sealed to said casing and closing said opening, a spring seat secured to the movable end of said bellows, a headed screw projecting into said bellows and beyond said seat, a spring held under compression between said seat and the head of said screw, a bell crank supported for pivotal movement within said casing, means connecting one arm of said bell crank to said movable end of said bellows, said connection being so constructed and arranged that said bell crank has positive equal movement with said bellows in both directions of movement of said bellows, a needle valve cooperating with said valve seat, and a connection between said needle valve and the remaining arm of said bell crank, the last mentioned connection being so constructed and arranged as to cause constantly positive equal movement of said needle valve in both directions with said remaining arm, said screw being movable to a position to engage the said bellows and move it to a position to positively unseat said valve.
30. 4. In a valve structure, in combination, a casing having a valve seat therein and an opening, an open ended bellows projecting into said casing and having its open end sealed to said casing, a cup-shaped member within said bellows with its bottom fixed to the closed end of said bellows, a cover over said bellows, a headed screw threaded through said cover with its head positioned in adjacent relationship with respect to the closed end of said bellows, a spring maintained under compression between the rim of said cup-shaped member and said head of said screw, a bell crank pivotally mounted within said casing, a slideable connection between one arm of said bell crank

and the closed end of said bellows, said connection being so constructed and arranged as to cause positive equal movement of the end of said arm in both directions with said closed end of said bellows, the other arm of said bell crank extending into intersecting relation with the extended axis of said valve seat, and a needle valve cooperable with said seat universally connected to said other arm, the last mentioned connection being so constructed and arranged as to cause constantly positive equal movement of said needle valve and said other arm in both directions axially of said valve seat, said screw being movable to a position to move said closed end of said bellows to positively unseat said valve.

5. An expansion valve structure including in combination, a housing having a valve seat therein, a needle valve member having the point thereof arranged in cooperative relation with said valve seat serving to control the passage of fluid therethrough, a fluid pressure responsive device for actuating said needle valve member, a bell crank arm serving to interconnect said fluid pressure responsive device and said needle valve member, said bell crank arm being pivotally connected to said fluid pressure responsive device for positive equal movement therewith in both directions, a universal connection for interconnecting said bell crank arm and needle valve member serving to permit a limited universal movement of said needle valve member with respect to its seat and at the same time serving to effect positive equal movement of said needle valve member with said arm in both directions, means in said universal connection serving to lock said needle valve member against rotation about its own axis and a fixed pivotal mounting for said bell crank arm within said housing whereby as said arm is moved said needle valve member will be moved toward or away from its seat in a direction parallel to its axis.

EDWARD R. DE LUIZ.
